FIG. 6.

INVENTOR,
James F. Wilson,
BY
A. D. Jackson
ATTORNEY

UNITED STATES PATENT OFFICE.

JAMES F. WILSON, OF WICHITA FALLS, TEXAS.

SUPPORT FOR TELEGRAPH LINE-WIRES AND THE LIKE.

1,266,736.

Specification of Letters Patent. Patented May 21, 1918.

Application filed July 31, 1917. Serial No. 183,672.

To all whom it may concern:

Be it known that I, JAMES F. WILSON, a citizen of the United States of America, residing at Wichita Falls, in the county of 5 Wichita and State of Texas, have invented certain new and useful Improvements in Supports for Telegraph Line-Wires and the Like, of which the following is a specification.

10 My invention relates to supports for telegraph and telephone line wires, electric light line wires, and the like, and the object is to provide simple and highly efficient brackets for holding such wires securely in place and 15 devices which are easily and quickly installed and devices which will hold the wires securely from post to post so that the wires will not drop to the ground except possibly between the posts where the break occurs in 20 a wire and to hold the wires in case of expansion of the wires so that the only dropping of the wires will be the sag between two posts. Other objects and advantages will be to provide devices that will endure 25 indefinitely as there will be nothing to decay. The devices will be fully explained in the following description and the invention will be more particularly pointed out in the claims.

Reference is had to the accompanying drawings which form a part of this application.

Figure 1 is a side elevation of the supporting apparatus, showing an ordinary post broken away. Fig. 2 is an enlarged detail 35 view of a clamp. Fig. 3 is a detail view of a clamp lock. Fig. 4 is a detail view of the insulation. Fig. 5 is a vertical section, taken substantially on the line 1—1 of Fig. 1. Fig. 6 is a plan view of the main bracket bar.

40 Similar characters of reference are used to indicate the same parts throughout the several views.

A post 1 of ordinary type is shown broken away at the bottom. The cross bar 3 has an 45 off-set to receive the post 1 and the bracket will be gained into the post in the usual manner so that the weight will be directly on the post. The cross bar or main bracket bar 3 is preferably made of metal. Braces 4 are 50 attached to the post 1 and to the bar 3 for making the bar 3 rigid. The wires 5 are clamped securely against longitudinal movement. Insulation blocks 6 are provided and 55 each insulation block 6 consists of two parts, the planes forming the meeting faces of the two parts being vertically arranged so that

the two parts can be clamped on the wire 5. The two parts of the block 6 are clamped on the wire by a spring clamp 7. The bar 3 has vertical openings 8 to receive the clamps 7. 60 After the insulation has been placed on a wire, it is placed in the clamp 7. The arms of the clamp will be sprung together and inserted in the vertical opening in the cross bar 3 and driven down to the positions illustrated. The insulation block 6 will be securely clamped on the wire so that the wire cannot move in the insulation or through the insulation 6. The insulation block 6 may be provided with flanges 9 at each end to 70 prevent the insulation blocks from moving longitudinally in the clamps 7. The clamps 7 are locked securely in the cross-bar 3 by wedge shaped keys 10 driven through horizontal recesses in the bar 3, the horizontal 75 openings intersecting partly the vertical recesses. One arm of the clamp 7 has a cut-out 11 to receive the key 10 so that the clamp will be securely locked against vertical movement in the bracket bar. The key 10 may be 80 serrated or notched on one edge, as at 12, to form slight shoulders on the key to prevent backward movement of the key through the bar 3. The shoulders will catch against the angle formed by the recess and the face of 85 the bar and thus prevent backward movement of the key after it is once driven through the bar 3.

There may be as many bars 3 on a post as may be necessary and there may be as many 90 clamps in each bar as may be necessary or expedient. Various changes in the sizes, proportions, and construction of the various parts may be made without departing from 95 my invention.

What I claim, is,—

1. A support for telegraph line wires and the like comprising a cross-bar having vertical openings and horizontal openings intercepting said openings, clamps secured in 100 said openings, flanged insulation in two parts carried by said clamps and clamped on the line wires by said clamps, and means in said horizontal openings for locking said clamps against vertical movement. 105

2. A support for telegraph line wires and the like comprising a cross-bar having vertical openings, therethrough, line engaging members, each consisting of a block of insulation in two parts for receiving a wire 111 and having faces meeting in a vertical plane, a clamp bent about the parts of said insula-

tion and having arms sprung together and inserted in one of said openings and clamping said insulation on the wire, and a key for locking the clamp in its opening.

- 5 3. A support for telegraph line wires and the like comprising a cross-bar having vertical openings therethrough and horizontal openings therethrough intercepting said vertical openings, line engaging members, 10 each consisting of an insulation block in two parts, a clamp bent about said insulation

and having arms sprung together, forcing said insulation on a wire and inserted through one of said vertical openings, one of said arms having a recess in the outside, 15 and a wedge-shaped key for locking said clamp in said opening inserted through one of said horizontal openings, engaging the recess in said arm.

In testimony whereof, I set my hand, this 27th day of July, 1917.

JAMES F. WILSON.
